UNITED STATES PATENT OFFICE.

EDWIN H. FLINT, OF CINCINNATI, OHIO.

TIME-LOCK.

SPECIFICATION forming part of Letters Patent No. 242,911, dated June 14, 1881.

Application filed September 9, 1880. (Model.)

To all whom it may concern:

Be it known that I, EDWIN H. FLINT, of Cincinnati, Hamilton county, Ohio, have invented a new and useful Improvement in Time-Locks, of which the following is a specification.

Locksmiths are familiar with a number of mechanical expedients for releasing the door of a bank safe or vault whose time-mechanism has stopped prematurely, so as to cause what is known as a "lock out." Some of these expedients, however, while of use for the special purpose of their creation, are inadequate for contingencies that sometimes arise which render it of great importance that the proper authorities should be enabled to obtain prompt access to the contents of the safe at any moment and while the guarding action of the timer may be in full activity. Other expedients have been devised to effect this object by the use of supplemental or extra sets of tumblers.

My invention relates to special opening devices constructed to operate with entire independence of the clock-work and with equal facility, both in the running and stationary conditions thereof, the arrangement of my special opening mechanism being such as to enable the safe-bolt work to be at any moment released by means of the ordinary tumblers by the concurrent consecutive acts of three persons, in the manner hereinafter explained, without the requirement of supplementary or additional tumblers.

The time-obstruction used by me for the purpose indicated, comprises two dogs or detents, of which either one is capable of preventing retraction of the safe-bolt work. Both of these detents are, in the normal action of the timer, released simultaneously, and in such action may be considered as one, and as then operating as adjuncts of the time-mechanism. On the contrary, their release by special manipulation is consecutive and in a prescribed order and wholly independent of the time-movement proper. Under any circumstances, whether by the timer or by special manipulation, their release after having been once set is a condition precedent to the release of the ordinary obstruction used during business hours. As in my above cited patent all the manipulations are effected through the

instrumentality of the ordinary arbor and permutation tumblers, no additional gatings nor supplementary tumblers being employed or necessary. The delay and publicity required for the assemblage of the several persons whose concurrent action is necessary to open the time-lock safe puts it out of the power of burglars to effect an entrance by intimidation of the persons in charge, while the entire independence of the special opening devices of the integrity or even presence of the time-movement proper adds an important element of safety and convenience.

In the accompanying drawings, Figure 1 is an elevation of a time-lock embodying my invention, the bolt-work being shown protracted and all the detents being set. Fig. 2 is a partial representation of the same, showing the lower time-detent released by means of the tumbler-mechanism, and the bolt-work partially retracted. Fig. 3 is a similar view, showing the remaining time-detent released and the bolt-work still further slightly retracted, in order to maintain such release and to hold the lock in condition for complete release by one in possession of the daily formula. In the above figures, portions of the tumbler-case are broken away. Fig. 4 is an elevation of the lock in its unlocked condition, the mechanism being set for temporary postponement and automatic assumption of the time-guarding action. In this view a portion of the dial-ring is broken away. Fig. 5 is a section of the line xx . Fig. 6 is a perspective view of the time-detents and a portion of their automatic releasing mechanism. Fig. 7 shows my adjustable automatic tappet detached.

The drawings contain no representation of the clock-work proper, which may be of any customary or appropriate construction.

A and F may represent, respectively, portions of the jamb and of the door of a bank safe or vault. B represents the safe-bolt work handle.

T represents the handle of the arbor that operates the permutation wheels or tumblers.

C are the safe-bolts, and D their connecting-bar, constituting the safe-bolt work. The bar D has the customary slot, d , for wrist b of handle B. Said bar also has the customary tongue, d' , whose impingement against the tumblers E in their unengaged position prevents

retraction of the bolt-work. Notches d'' d''' in bar D permit said bar to slide past the time-detents in the released condition of the latter.

H may represent a time mechanism, including any suitable clock-work.

With the exception of the notches d'' d''' all the above-mentioned parts may be of any well-known or customary form, and require no specific description.

10 My time mechanism has preferably an annular dial, I, that is adapted to revolve upon three rollers, J J' J'', of which one roller, J, is fastened to the mainspring-shaft K, whose pinion L meshes in a circular rack, M, on the 15 inner margin of said annular dial.

N represents the customary tappet or projection from the rear of the dial for operating at the assigned period on the releasing mechanism of the time-detents in the normal operation 20 of the time-lock.

O represents the customary stump for arresting the motion of the timer on discharge of its functions.

My time-detents consist of two bent levers, 25 P P', of which each is held to its normal or locked condition by a spring, Q. In this position the heads p of the detents stand immediately in rear of the bar D, the lower detent, P, projecting slightly in advance of the upper 30 detent, P'.

A sliding rod or bar, R, is pivoted at r to a lever, S, whose other extremity rests upon the lower detent, P. The rod R is notched at r' at its upper end to receive a pin upon the arm 35 p', that projects from upper time-detent, P'.

U is the lever of the time-releasing mechanism. One end of said lever occupies notch r'' in rod R, and its other end extends behind the dial sufficiently to receive the impact of 40 tappet N, so as at the proper instant to elevate the rod R.

G is a rigid plate or flange, which, being located behind the heads p of detents P P', receives the stress of the retracted bolt-work. 45 This elevation of rod R operates to push the two time-detents, P P', into their unlocked positions, and this is what takes place at every normal discharge of the time-mechanism functions. It will be perceived that the detents in 50 such position are directed to the notched portions d'' d''' of bar D, and that in such position they no longer oppose the retraction of the bolt-work.

In order to unlock the safe the ordinary custodian (in the above position of the time-detents) has merely to set up the tumblers in gate with the tongue d' and withdraw the bolt-work.

For the ordinary diurnal functions of a time and permutation lock the above mechanism is 60 sufficient; but such mechanism is worse than useless in event of premature stoppage of the timer or the approach of a conflagration or other urgent circumstance rendering it necessary to open the safe instantly and out of business hours.

To enable authorized persons under proper safeguards to open the safe after a lock-out,

or even during the active custody of the time mechanism, I have provided the following special releasing devices.

V V' are two similar fences or angle-bars, of which each has a rectangular projection or arm, v. The arm of each fence in succession is caused to drop into the ordinary gatings of the tumblers when the latter are set up to the 75 proper respective secret formulas in their determined and proper sequences, as hereinafter explained. Each fence, being secured to the lock-case by a pin, w, that occupies a slot, w', in the fence-plate, is susceptible of a sliding as well as 80 a vibratory motion. This mode of attachment, in conjunction with a spring, W, compels each fence to assume, when at liberty, the retracted converging position shown in Fig. 1, so as to readily engage in the tumblers when the 85 latter are properly gated for that purpose. Such engagement having been secured, the first operator presses the bolt-work gently forward with one hand, and then rotates the tumbler-arbor forward with his other hand, so as to drag the 90 fence V in direction of the arrow until, impinging on the heel p'' of the corresponding detent P, it operates to swing said detent so as to confront the notched portion d' of bar D. The operator then, still holding the tumbler-arbor to the position last named, retracts the 95 bolt-work, (see Fig. 2), so as to prevent the return of the detent to its locking position. The more projecting lower detent, P, is the first to be operated, as above, and, becoming 100 thereby engaged in the notch d', ceases for the time being its dogging action. A similar manipulation by the second operator of the upper detent, P', in conformity with its appropriate formula likewise, in turn, engages it 105 in its proper notch d''', and both detents having been thus rendered inactive the cashier has merely to set up the tumblers to the ordinary formula to be enabled to retract the bolt-work and open the safe.

Associated or not with the above-described special releasing mechanism may be a device to enable the custodian, before closing the safe, to set the timer to assume control at any desired moment. For this purpose I provide 115 a trip-lever or trigger, X, which depends from a pivot, x, and has a shoulder, x', capable of being engaged over a pin, u, that projects from lever U, so as to hold the latter to its releasing position. The trigger X is at the 120 proper instant disengaged by the impact against its oblique extremity x'' of a pin, Z, that projects from the dial. In order that the pin Z may be adjustable to any part of the dial-circuit it has a screw-shank, z, which is 125 tapped into a nut, z', that occupies an undercut annular groove, i, in the dial. Upon slightly unscrewing the pin Z the operator can shift the pin to any point on the dial-circuit, according to the moment at which he desires 130 the timer to assume its functions, and then, by tightening the screw, can fix the pin to its place of adjustment.

2 and 3 may represent holes for as many

pins, either or both of which may be used when one or both special operators desires to render his detent inoperative.

4 may represent customary hole for a trial-
5 key.

For manipulation of the special releasing mechanism each special operator, in succession and in the assigned order, grasps the bolt-work handle B in his left and the tumbler-
10 handle T in his right hand. To insure the proper operation of the special releasing mechanism each respective special operator is furnished with a secret formula, which, for a four-tumbler lock, is substantially such as follows, the numbers being, of course, arbitrarily
15 selected for each lock:

Special formula No. 1: First, retract and then slightly protract bolt-work; turn tumbler-arbor to right 5, stop 67; left 2, stop 39; right
20 1, stop 26; left stop 17, right stop 12. Again retract and slightly protract bolt-work.

Special formula No. 2: Right 5, stop 19; left
2, stop 82; right 1, stop 69; left stop 58, left
25 stop 63. Again retract and slightly protract bolt-work.

Daily formula: Left 5, stop 31; right 2, stop
22½; left 1, stop 83; right stop 82½. Completely retract the bolt-work and open the door.

The above-described preferred form of my
30 invention may be varied in non-essential particulars. For example, one of the time-detents and its corresponding fence may be omitted or be removed, and the lock will remain time-guarded and be specially releasable by the aid of one special operator.

Mechanical expedients, such as V V' and their described or equivalent accessories, may be employed in connection with special detents and without a timer; but as I contemplate
40 making such a lock the subject of special application for patent, I lay no claim to such under this.

An incidental advantage of my peculiar provision of two time-detents, which operate independently of the tumblers and of each other to guard the bolt-work, is that should the tumblers be forcibly driven in so as to remove the ordinary obstruction the bolt-work remains securely held by these independent and inaccessible
50 obstructions.

By the phrase "ordinary tumblers" is meant the tumblers that are employed in the ordinary manipulations of the lock during business hours and to the exclusion of supplementary
55 or additional tumblers, none such being used or required in my lock.

In comparison with such devices as employ supplementary systems of tumblers my device possesses the important advantages of relative compactness and simplicity, with greater safety 6c against clandestine operators, less encroachment on the interior capacity of the safe, and greater exemption from risk of derangement.

Having thus described my invention, the following is what I claim as new and desire to 65 secure by Letters Patent:

1. In a time-lock, the combination of suitable door-bolt work, independent time and non-time obstructions, and releasing mechanism for the time-obstructions operated independently of the timer, and whether the latter is running or not, by the action of the same tumblers which release the non-time obstructions, but under separate or distinct manipulation thereof. 70

2. In the described combination with a stack of rotary tumblers and an independently-guarding time mechanism whose detents when acting automatically simultaneously engage with and disengage from the safe-bolt work, the two 80 consecutively-operated fences V V' for optional release of the time-obstruction through the instrumentality of the tumblers after each manipulation of the tumblers to a special formula, in the manner set forth. 85

3. In combination with safe-bolt work having tongue-detent d' and notches d'' d''', a stack of ordinary single-gated rotary tumblers, E, and two detents, P P', operated automatically and simultaneously by the timer, the means, substantially as described, for consecutive release of said detents through the instrumentality of the tumblers independently of timer, and whether the timer be running or not running, substantially as set forth. 90

4. In the described combination, with independently attached, connected, and operating time and tumbler locks, the notched connecting bar or rod D d d' d'' d''', detents P P', and the fences V V', for the purposes set forth. 95

5. The combination, with the detents P P' and retracting-lever U, of the trip-lever X and the tappet Z, adjustable on the time-dial I, substantially as and for the purposes set forth.

In testimony of which invention I hereunto 105 set my hand.

EDWIN H. FLINT.
